Design for carpet.
Patented July 4, 1865.

Henry G. Thompson of New York N.Y. Des. 2124

Assignee to

The Hartford Carpet Company of Hartford, Ct.

Letters Patent No. 2124, Dated July 4th 1815.

Design for a Carpet pattern

The schedule referred to in these Letters Patent and making part of the same.

To all whom it may concern

Be it known that of Henry G.

Thompson of the City, County and State of New York, have invented or produced a new and original

Design for a Pattern to be wrought into two ply

Strains and other carpeting, in colors similar to those painted on the drawings accompanying this specification, or in other colors substituted in the place of those painted on the drawings herewith; and I do hereby declare that the drawings accompanying this specification, do give and convey to any one skilled in the Art of Carpet weaving a more defined and thorough description of the nature of my invention than it is in the power of language otherwise to convey, and is sufficient to enable any one skilled in the Art of Carpet weaving to use my invention.

What I claim as my invention and desire to secure by Letters Patent, is the configuration of the Design herewith annexed, when made by being wrought into two ply Strain or other carpeting in the form similar to the drawings accompanying this Specification.
